(57) CLAIM

The ornamental design for a beverage bottle, as shown and described.

DESCRIPTION

FIG. 1 is a front elevation view of a first embodiment of a beverage bottle showing our new design;

FIG. 2 is a back elevation view thereof;

FIG. 3 is a left elevation view thereof; and

FIG. 4 is a right elevation view thereof.

The broken line showing of the environment is for illustrative purpose only and forms not part of the claimed design.

1 Claim, 2 Drawing Sheets

FIG. 3FIG. 4
